METHOD AND MACHINE FOR FORMING
FIBROUS SLIP COVERSLeon E. La Bombard, Fulton, N. Y., assignor to
Oswego Falls Corporation, Fulton, N. Y., a corporation of New York

Application November 11, 1935, Serial No. 49,217

9 Claims. (Cl. 93—36.5)

This invention has for its object, a method of forming slip covers for containers with the lower portion of their cylindrical rims, or flanges, expanded slightly outward in order that the slip covers may be readily placed, or started, on the containers and snugly fit the containers when in place thereon, and also a particularly simple and efficient machine for carrying out the method.

10 The method relates to forming the slip cover with its rim, or flange expanded slightly, and at the same time forming the rim so it will snugly fit the container.

The method consists in forming the slip cover with the cylindrical flange having an inside diameter not greater than the outside diameter of the container, placing the flange of the slip cover upon a mandrel, gripping a narrow portion of the flange intermediate of its ends between the 15 mandrel and a roller, subsequently compressing the lower portion of the flange between the roller and the mandrel while the same are in motion, releasing the flange from between the roller and mandrel, and removing the flange from the 20 mandrel.

That is, a comparatively narrow portion of the flange is first gripped between the roller and the mandrel and subsequently, the lower portion of the flange extending from the gripped portion to 25 the lower edge is compressed between the roller and the mandrel, while the roller and mandrel are revolved thereby compressing the thickness of the lower portion of the flange and accordingly stretching the same, or increasing it slightly in diameter.

30 The slip cover may be formed in any suitable manner by the methods now well known to those skilled in the art. Usually, the cylindrical flange consists of a narrow band severed from a tube 35 wound of multi-layer paper formation. This band is placed into a machine which automatically crimps the upper edge or end of the band into interlocking engagement with the periphery of a paper disk.

40 It is necessary that the cylindrical flange of the slip cover fit the upper end of the cylindrical container more or less tightly according to the contents of the container. Where the container is used for liquid and semi-liquid products, it is 45 essential that the flange of the slip cover fit the container tightly. To accomplish this result, it is necessary to form the flange, or the tube from which it is severed, a few thousandths of an inch smaller than the outside diameter of the 50 container barrel. While this results in a tight 55

joint between the slip cover and the container, it is extremely difficult to put the slip cover on the container. This problem has been appreciated in the paper container art for some time, and various attempts have been made to overcome it. 5

I have found that a slip cover formed as shown in my copending application, Sr. No. 757,165 is very satisfactory in that it can be readily and conveniently applied to and removed from the container, and when on the container effects a 10 leak-proof closure. This slip cover is so formed that the cylindrical flange is initially a few thousandths of an inch smaller inside diameter than the outside diameter of the container wall. The flange of the container is then processed so 15 that the lower portion of the flange is increased slightly in diameter so that there is a clearance between that portion of the flange and the outside of the container wall of a few thousandths of an inch. This stretched or expanded lower portion 20 of the flange extends parallel with the wall of the container, and provides a means whereby the slip cover can be conveniently started on the upper end of the container. This stretching or 25 expanding is done in such manner as not to increase the diameter of the upper portion of the flange with the result that that portion, when the slip cover is on the container, effects a liquid tight joint between the two.

The invention, as pertaining to the machine, 30 consists in the novel features and in the combinations and constructions hereinafter set forth and claimed.

In describing this invention, reference is had 35 to the accompanying drawings in which like characters designate corresponding parts in all the views.

Figure 1 is a top plan view, partly in section, of 40 a machine for carrying out this method.

Figure 2 is a side elevation, partly in section, 45 of the machine shown in Figure 1.

Figure 3 is an enlarged sectional view of parts 50 seen in Figures 1 and 2, forming part of the mechanism for compressing the flange of the slip cover on the mandrel.

Figure 4 is a fragmentary, sectional view of the 55 drive mechanism for the machine.

Figure 5 is an end elevation view looking to the left in Figure 2.

Figure 6 is a fragmentary, partly sectional, view 60 of a container and slip cover.

Figure 7 is an enlarged, fragmentary, sectional view of the slip cover and contiguous portions of the roller and mandrel with the flange of the 65

cover placed upon the mandrel, and the bead of the roller contacting the flange.

Figure 8 is a view, similar to Figure 7, with the roller moved toward the axis of the mandrel under pressure, and showing the formation of the flange of the slip cover.

This machine comprises a suitable frame, a mandrel having an axle, or shaft, mounted in the frame, a roller, and a support therefor mounted to carry the roller radially toward and from the mandrel, a feed carriage movable along the frame and operable to place the slip covers on the mandrel, and mechanism for rotating the mandrel, operating and timing the operation of the roller, and operating and timing the operation of the carriage.

C, Figure 6, designates a container, this being usually formed up of paper-board, or paper stock. S designates the slip cover having a cylindrical rim, or flange R, for slipping over the container, the slip cover including a suitable head H, and the cylindrical rim R. The rim R is initially formed so that the inside diameter thereof is a few thousandths of an inch smaller than the outside diameter of the container C.

10 designates generally, the frame of the machine.

12 designates the rotatable mandrel, and 13 a roller for coacting therewith. The mandrel 12, as here shown, is mounted upon a shaft 14 journalled in anti-friction bearings 15, 16, mounted in the frame 10. The mandrel 12 is mounted on one end of the shaft 14 overhanging the contiguous portion of the frame 10. A suitable drive wheel 17 is mounted on the other end of the shaft, this being here shown as a sprocket wheel. One of the bearings, as 16, is fixed in the frame from endwise movement, and the other bearing 15 is mounted to float, or have an axial movement relative to the frame 10, but it is held from axial movement relative to the shaft 14 by motion transmitting means mounted on the shaft by means of which power is taken from the shaft to actuate other moving parts of the machine.

15 The motion transmitting means includes a worm 18 slidably keyed to the shaft 14 and held in position from sliding movement by spacing rings 19 and 20 interposed between the ends of the worm and the inner ring of the bearing 15, and the inner ring of the bearing 16. The inner ring of the bearing 15 thrusts against the shoulder 21 on the shaft, and the outer ring of the bearing 16 is held between two shoulders on the frame 10, provided in any suitable manner, see Figure 4. The sprocket 17 is slidably keyed to the spindle 14, and its hub is thrust against the inner ring of bearing 16 by nut 22 threading on the end of shaft 14.

20 A stripper is mounted axially of the shaft 14 for removing the finished covers from the mandrel. This stripper comprises a rod 23 slidably axially of the shaft 14 and having a head 24 at its end, within the mandrel, and a disk 25 secured to the head 24 for pressing against the heads of the covers. The disk 25 and mandrel 12 are provided with holes 26 to permit the covers to be readily placed on and removed from the mandrel by releasing any vacuum. The other end of the rod is secured to a plunger 27, also slidably mounted in the shaft 14 and extending beyond the end of the shaft where it coacts with actuating mechanism. The actuation of the plunger 27, by its actuating mechanism, is against a returning spring 28 encircling the rod 23 within the shaft and thrusting at one end against the

plunger 27, and at its other end against a sleeve 29 pressed into the shaft. The rod and plunger are secured together by a pin 30.

The roller 13 is mounted on a stud 31 carried by a support, here shown as a lever 32 having a hub 33 mounted on a rod or overhanging arm 34 suitably supported by brackets 35 on the frame 10. The lever is here shown as arcuate and extending above and crosswise of the mandrel 12. The stud is located between the ends of the lever 32 and directly above the mandrel so that during slight pivotal movement of the lever 32, the roller moves substantially radially relatively to the mandrel. The free end of the lever 32 is connected to suitable timing and actuating mechanism to be described. Suitable anti-friction bearings 36 are interposed between the roller 13 and the stud 31.

The mandrel 12 is formed with a base portion having a cylindrical surface 37 which fits the inner surface of the margin of the rim R of the slip cover S, and with a reduced advance portion 38 which is located within and spaced from the base portion 40 of the rim when the rim is on the mandrel so that the base portion 40 of the rim is unrestrained during the rolling operation, see Figure 7.

The roller 13 is formed with a peripheral cylindrical surface 41, and with an annular bead 42 at the base of the surface 41, and is relieved at 43 at its outer end so as not to engage the base 40 of the rim R. The roller 13 is so arranged, or mounted, upon the lever 32 that the bead 42 coacts with the inclined surface or zone 44 and surface 38 of the mandrel 12. Thus, when the roller 13 is moved radially against the rim or flange R on the mandrel 12, the rim R is first contacted by the narrow bead 42. That is, the flange R is first clamped between the surfaces 38, 44, of the mandrel and the bead 42, 40 the purpose for so doing will appear later.

Upon further movement of the roller toward the mandrel, the outer portion of the flange R is compressed between the cylindrical surfaces 37, 41, of the mandrel and roller respectively. 45 The spindle 14 and the mandrel are continuously rotated by a suitable drive connection to the sprocket 17 from the main cover forming machine. By this rotary movement of the mandrel and roller, the outer portion of the flange R 50 is rolled out or reduced in thickness, as indicated at 45, Figure 8, and inasmuch as the surface 37 of the mandrel 12 is of such diameter as to snugly receive the flange R as initially formed, the compression of the fibers in the outer portion of the rim results in stretching or expanding said portion of the flange to increased diameter. This expanded portion is definitely defined at its upper margin by the clamping of the flange between the bead of the roller and the 55 complementary surfaces on the mandrel. I have found that if the roller and mandrel are not formed as described, the stresses resulting from the compression of the fibers in the outer portion extends to the upper or base portion 40 of the 60 flange. Inasmuch as the upper portion 40 of the flange must fit the container snugly, it is essential that the flange at this point be not disturbed so as to vary its diameter, and this result is obtained by clamping the flange of the 65 cover between the bead and the mandrel preliminary to the compression of the outer portion of the flange.

The axis of the roller 13 is tilted slightly relative to the axis of the mandrel 12, as shown in 75

Figures 1 and 3. This is done for the purpose of preventing the slip cover from running off from the mandrel during the compression operation on the flange of the slip cover. If the axis of the roller 13 extended parallel in both planes relative to the axis of the mandrel 12, the slip cover would have a tendency to thread off from the mandrel during the rotary motion. The bead 42 of the roller 13 and the inclined surface 44 of the mandrel are somewhat exaggerated in the drawings in order to better illustrate the operation of the machine. In practice, the bead and the inclined surface 44 vary only a few thousandths of an inch in diameter from the cylindrical surfaces 37, 41.

Having now described the general operation of the mandrel and roller, and the effect produced upon the flange of the slip cover, I proceed to describe the mechanism necessary to render the machine automatic in operation.

50 designates generally a carriage for feeding the covers onto the mandrel. The carriage 50 is slidably supported on the overhanging shaft or arm 34, the carriage being provided with 25 spaced apart bosses 51 formed with a bore to slidably receive the arm 34, and the carriage is also provided with a depending arm portion 52 formed with a boss 53 bored to slidably receive the arm 54 which is supported and carried by 30 a depending arm 55 secured to the end of the arm 34. The carriage 50 is provided at its end toward the mandrel 12 with a receiver for receiving the covers from the cover making machine, and also with means for selecting one 35 cover at a time and transferring it onto the mandrel 12. This transferring or feeding means, as here shown, comprises a rotatable head 56 journalled on suitable bearings on the end of shaft 57 which is slidably mounted in the carriage and arranged in axial alinement with the shaft 14. The shaft 57 is provided, a substantial portion of its length, with a bore to receive the helical compression spring 58. The rear end of the shaft 57 is bifurcated, or slotted, as at 59. 40 A retaining bar 60 is secured to the end of the carriage extending across the bore thereof and through the slot 59. This construction permits sliding movement of the shaft 57 relative to the carriage 50, and at the same time the shaft 57 is held from rotation. A cap 61 is secured to the bifurcated end of the shaft 57 and overlies the face of the retaining bar 60. One end of the compression spring 58 abuts against the retaining bar 60 and tends to urge the shaft 57 45 toward the mandrel 12, such movement being restrained by the cap 61 thrusting against the bar 60. The head 56 is located in the cover receiver 63. The carriage is actuated in timed relationship along the guides 34, 54 by mechanism to be presently described.

As previously stated, a power drive is connected to the sprocket 17 from the cover making machine, this effects constant rotation of the shaft 14 and the worm 18. The frame 10 65 is provided with a suitably journalled shaft 65 extending transversely thereof and through the side members of the frame. This shaft has keyed to it intermediate its ends, a worm gear 66 arranged to mesh with the worm 18, said gearing 70 transmitting continuous rotation to the shaft 65. The rear end of the shaft 65 has keyed to it a crank 67 and to the crank pin of which is suitably connected one end of connecting rod 68, the other end being suitably connected to the carriage 50, as at 69. Accordingly, during operation

of the machine, the carriage is reciprocated periodically toward and from the mandrel 12, and as the slip covers are delivered to the receiver 63 they are in turn transferred to the mandrel 12. The purpose of the compression spring 58 in shaft 57 is to place each cover on the mandrel with the same pressure.

The lever 32 is actuated about its pivot 34 to move the roller 13 toward and from the axis of the mandrel 12 by motion transmitting mechanism to be now described.

A cam 70 is secured to the forward end of the shaft 65 and is formed with a lobe 71 as here shown extending slightly over one-half its circumference. A lever 72 is pivoted to the frame 15 10 as at 73 and one end provided with a follower 74 coacting with the periphery of the cam 70. The action of the cam imparts a rocking movement to the lever 72 about its pivot 73. The lever 72 is provided with a projection 75 coacting with 20 the lower end of rod 76, the upper end of which is pivotally connected to lever 32, as at 77. The lower end of the push rod 76 is guided in a suitable bracket 78, and is provided with a collar 79. A helical compression spring 80 is inserted between the boss of the bracket 78 and the collar 79. The compression spring 80 tends to move the rod 76 downwardly to bring the roller 13 into contact with the mandrel 12. The collar 79 is adjustable to vary the pressure between the roller and the mandrel. When the lobe 71 of cam 70 coacts with the follower 74, the lever 72 is rotated in a counterclockwise direction Figure 2, to lift the push rod 76, effecting separation of the roller 13 from the mandrel 12. 35

A second cam 90 is also secured to the forward end of the shaft 65. As here shown, the cam 90 is rotatably mounted upon the hub of the cam 70 and is secured thereto in an adjustable manner by screws 91. The cam 90 is provided with a lobe 92 of comparatively short length. To the rear of the frame 10, an angular lever 93 is pivoted as at 94. One arm of the lever 93 is arranged to coact with the plunger 27, and the other arm is provided with a follower to coact with the cam 90. When the lobe 92 engages the follower of lever 93, the lever is rocked in a clockwise direction Figure 2, forcing the plunger 27 inwardly and effecting axial movement of the disk 25 to remove the completed cover from 40 the mandrel 12. The crank 66, cams 70, 90, are so adjusted relatively that the carriage is moved to the left Figure 2, transferring a cap from the receiver 63 to the mandrel 12, and at the same time the lobe 71 of cam 70 engages with the follower 74 causing the roller 13 to be elevated, or moved away from the mandrel 12 to permit the flange of the slip cover to be applied to the mandrel. Upon further operation of the device, the carriage is moved to the right Figure 2, and 45 50 the lobe 71 passes out of contact with the follower 74, permitting the roller 13 to be pressed against the flange of the slip cover by action of the spring 80.

It will be observed that the spindle 14 makes 65 several revolutions to one revolution of the shaft 65. This permits the roller 13 to act on the flange of the cover throughout the periphery thereof to compress the fibers therein. Slightly after the time the lobe 71 of cam 70 engages the follower 74 70 to release the roller 13, the lobe 92 of cam 90 engages the follower of lever 93 effecting a quick ejection of the slip cover which falls into any suitable container, not shown. The frame 10 is carried by a suitable bracket 96 which is attached 75

to the main cover forming machine, not shown, and is additionally supported by the rod 97. The sprocket 17 is driven at such speed from the cover forming machine as to permit the operation on 5 the flange of the cover at the same speed that the covers are produced by the machine.

What I claim is:

1. The method of forming fibrous slip covers for fibrous containers consisting in initially forming the flange of the cover of internal diameter not greater than the outer diameter of the container, applying the flange on a mandrel, preliminarily clamping the flange at an intermediate zone between the mandrel and a roller, subsequently compressing the fibers of the flange below said intermediate zone while the roller and mandrel are rotated, releasing the roller, and removing the flange from the mandrel.

2. The method of forming fibrous slip covers for fibrous containers consisting in initially forming the flange of the cover of less internal diameter than the outer diameter of the container to which the cover is to be applied, placing the flange of the cover on a mandrel, preliminarily clamping the flange at an intermediate zone between the mandrel and a roller, subsequently compressing the flange below said intermediate zone between the roller and the mandrel while the same are rotating, releasing the roller, and 30 removing the flange from the mandrel.

3. The method of forming fibrous slip covers for fibrous containers consisting in initially forming the flange of the cover of internal diameter less than the outer diameter of the container to which the cover is to be applied, gripping the flange at an intermediate zone between the bottom and top thereof, and while gripped, subsequently compressing the fibers of the bottom portion of the flange, thereby slightly increasing the 40 diameter of the lower portion of said flange.

4. A machine for forming flanges of fibrous slip covers with the bottom portion of the flange of greater diameter than the upper portion, said machine comprising a frame, a mandrel rotatably mounted in said frame, said frame extending beyond the end of the mandrel, a carriage slidably mounted on said frame extension toward and from the end of the mandrel and being provided with a transfer head arranged coaxially with the mandrel, a cover receiver arranged in juxtaposition to the mandrel and said transfer head, a support pivotally secured to the frame, a roller carried by said support, said support being movable about its pivot to bring said roller into 50 and out of contact with the flange of the cover on the mandrel, means operable to successively slide said carriage on said frame extension toward the mandrel to transfer a cover on the end of the mandrel; move said support to bring the roller into engagement with the flange of the cover and subsequently out of engagement with the same; and to remove the cover from the mandrel, and means for imparting rotary motion to the mandrel and said roller while the roller is in engagement with the flange of the slip cover, said roller and mandrel being provided with means cooperable while 40 the roller is in engagement with the flange of the cover to preliminarily grip said flange at an intermediate zone and to compress the lower portion of said flange, and means for imparting rotary motion to said mandrel during such press- 45 ing operation.

7. In a machine for forming flanges for fibrous slip covers with the bottom portion of the flange of greater diameter than the upper portion, said machine comprising a frame, a mandrel rotatably mounted in said frame, said frame extending beyond the end of the mandrel, a carriage slidably mounted on said frame extension toward and from the end of the mandrel, a transfer head carried by said carriage and arranged coaxially with said mandrel and having yielding axial movement relative to the carriage, a cover receiver arranged in juxtaposition to the mandrel and said transfer head, a roller journaled on the frame and being movable into and out of engagement with the flange of the cover on the mandrel, means operable to successively slide the carriage toward the mandrel to transfer a cover from said receiver to the mandrel; move said roller into and out of engagement with the flange of the cover, and subsequently remove said cover from the mandrel, and means for imparting rotary motion to the mandrel while the roller is in contact with the flange of the cover on the mandrel.

8. In a machine for forming flanges of fibrous slip covers with the bottom portion of the flange of greater diameter than the upper portion, said machine comprising a frame, a mandrel journaled in the frame, a support pivoted to the 70 mandrel and said transfer head, a roller carried by said support, said support being movable about its pivot to bring said roller into and out of contact with the flange of the cover on the mandrel, means operable to successively slide said carriage on said frame extension toward the mandrel to transfer a cover on the end of the mandrel; move said support to bring the roller into engagement with the flange of the cover and subsequently out of engagement with the same; and to remove the cover from the mandrel, and means for imparting continuous rotary motion to said mandrel.

frame and being provided with a roller, said support being movable about its pivot to bring said roller into and out of engagement with the mandrel, means yieldingly holding said support with the roller in mandrel engaging position, and means operable to periodically move said support to carry said roller out of engagement with the mandrel, and transfer means operable during said last mentioned operation to transfer 10 a slip cover onto the mandrel.

9. A machine for forming flanges of fibrous slip covers with the bottom portion of the flange of greater diameter than the upper portion, said machine comprising a frame, a mandrel rotatably mounted in said frame, said frame extending beyond the end of the mandrel, a carriage 15 slidably mounted on said frame extension toward and from the end of the mandrel and be-

ing provided with a cover transfer head arranged coaxially with the mandrel, a support movably mounted on the frame and a roller carried by said support, and said support being movable to bring the roller into and out of contact with said mandrel, means operable to successively slide said carriage on said frame extension toward the mandrel to transfer a cover on the end of the mandrel; move said support to bring the roller into engagement with the 10 flange of the cover and subsequently out of engagement with the same, and to remove the cover from the mandrel, and means for imparting rotary motion to the mandrel and said roller while the roller is in engagement with the 15 flange of the slip cover.

LEON E. LA BOMBARD.
